DESIGN FOR A CASTER

Frederic W. Parkhill, Kansas City, Mo., assignor
of one-fourth to Harman R. Brown and one-
fourth to Walter E. Ludwig, both of Kansas
City, Mo.

Application September 15, 1941, Serial No. 103,353

Term of patent 14 years

To all whom it may concern:

Be it known that I, Frederic W. Parkhill, a citizen of the United States, residing at Kansas City, in the county of Jackson and State of Missouri, have invented a new, original, and ornamental Design for a Caster, of which the following is a specification, reference being had to the accompanying drawing, forming a part thereof.

Fig. 1 is a side elevational view of the caster, showing my new design.

Fig. 2 is an edge elevational view thereof; and
Fig. 3 is a top plan view thereof.

I claim:

The ornamental design for a caster, as shown.

FREDERIC W. PARKHILL.
